UNITED STATES PATENT OFFICE.

CHARLES GREER, OF NEW CASTLE, PENNSYLVANIA.

DESIGN FOR A DRINKING-GLASS.

44,059.

Specification for Design.

Patented May 20, 1913.

Application filed January 22, 1913. Serial No. 743,669. Term of patent 14 years.

To all whom it may concern:

Be it known that I, CHARLES GREER, a citizen of the United States, residing at New Castle, in the county of Lawrence and State of Pennsylvania, have invented a new, original, and ornamental Design for a Drinking-Glass, of which the following is a specification, reference being had to the accompanying drawing, forming part hereof, in which—

Figure 1 is a side view of the glass, showing my design, Fig. 2 is a central longitudinal section, and Fig. 3 is a cross section on the line 3—3 of Fig. 1.

The thin upper half *a* of the glass is flared or turned outward, the lower and thicker half *b* being slightly rounded or convex, and a ridge or beveled shoulder *c* is formed at the junction of such parts *a*, *b*, such ridge or shoulder constituting the most distinctive feature of the design.

I claim:—

The ornamental design for a drinking glass, as shown.

CHARLES GREER.
